UNITED STATES PATENT OFFICE.

JOHN F. OTT, OF ORANGE, NEW JERSEY, ASSIGNOR TO NEW JERSEY PATENT COMPANY, OF ORANGE, NEW JERSEY, A CORPORATION OF NEW JERSEY.

APPARATUS FOR APPLYING PIGMENT TO ENGRAVED ENDS OF PHONOGRAPH-RECORDS.

No. 813,514.

Specification of Letters Patent.

Patented Feb. 27, 1906.

Application filed September 22, 1904. Serial No. 225,524.

To all whom it may concern.

Be it known that I, JOHN F. OTT, a citizen of the United States, and a resident of 75 High street, Orange, New Jersey, have invented certain new and useful Apparatus for Applying Pigment to Engraved Ends of Phonograph-Records, of which the following is a specification.

As now constructed phonograph-records are generally beveled at one of their ends, and on the beveled surface thus formed is engraved the name of the particular selection and generally the trade-mark of the manufacturer of the goods. The materials of which phonograph-records are now made are dark in color, and consequently the engraved lettering would be difficult to read. It is therefore desirable that the engraved matter should be filled in with some contrasting pigment, such as white lead. In applying such pigment it is necessary that it should be applied very uniformly with sufficient rapidity to make the operation economical from the manufacturing standpoint and in such a way as to not require continued handling of the record to possibly injure the surface thereof.

My improved machine has for its object and design the accomplishment of these desirable ends.

Broadly stated, the invention consists of a rotating mandrel on which the phonograph-record or other talking-machine record is applied so as to properly present the end or face carrying the engraved matter, in combination with a pigment-applying roller normally withdrawn from the record, but movable into engagement with the same to apply pigment to the engraved face or end thereof.

The invention also consists in details of construction, all as will be more fully hereinafter described, and set forth in the claims.

In order that the invention may be better understood, attention is directed to the accompanying drawings, forming part of this specification, and in which—

Figure 1 is a plan view of the improved machine, showing the pigment-applying roller in its withdrawn position; Fig. 2, a front elevation of the same; Fig. 3, a detail plan view showing the pigment-applying roller in engagement with the record, and Fig. 4 a sectional view on the line 4-4 of Fig. 1.

In all of the above views corresponding parts are represented by the same numerals of reference.

A base 1 carries a suitable stand 2, in which is mounted the shaft 3, carrying a tapered mandrel 4, with which frictionally engages the phonograph-record or other talking-machine record 5, usually having a beveled face or end 6, carrying the engraved matter. (Not shown.) On the shaft 3 is mounted a pulley 7, with which engages a belt 8, leading to any convenient source of power. A second belt 9 extends from the pulley 7 to a pulley 10 on a suitable counter-shaft 11, mounted in bearings 12, carried by the base 1. On the end of the counter-shaft 11 is a supply-roller 13, made, preferably, of felt or some other good absorbent material, and dipping within a pigment-tank 14. This pigment-tank contains any suitable liquid pigment, such as a mixture of white lead in linseed-oil, and the level thereof is maintained by adding fresh pigment as the supply becomes exhausted in use. A wiper 15 bears elastically against the face of the supply-roller 13 to prevent more than a thin film of the pigment adhering to the same.

Bearing on the supply-roller 13 is the pigment-applying roller 16, which is also preferably made of felt and which rotates on a swinging arm 17, pivoted on the support 18. At the free end of the swinging arm 17 is a small handle 19, movable longitudinally thereon, by which the arm may be swung, and pressing the pigment-applying roller 16 against this handle is a spring 20. The pigment-applying roller 16 rests by gravity on the supply-roller 13, and the rotation of the latter roller in the direction of the arrow (see Fig. 4) carries the pigment-applying roller against a wiper 21, by means of which the supply of pigment thereon may be distributed and any surplus removed, as will be understood.

The operation of the machine will of course be obvious. The phonograph-record is applied to the rotating mandrel 4 and rotates frictionally therewith. Pigment from the supply-roller 13 will be furnished to the applying-roller 16, so that the face of the latter will be always covered with a very thin film of the pigment. By moving the pigment-applying roller 16 over into engagement with the

beveled face of the record pigment therefrom will be applied to the record, so as to fill up the engraving thereon. When the record is removed from the mandrel, it is wiped lightly with a cloth, so as to remove the surplus pigment, leaving only the engraved matter filled therewith. By pressing inward on the handle 19 to move the pigment-applying roller 16 nearer the pivot of the lever 17 and against the tension of the spring 20 the pigment-applying roller will be properly engaged with the record regardless of its position on the mandrel. Phonograph-records are made so accurately, however, that their position on the mandrel will not vary much over a quarter of an inch, so that very little adjustment of this kind requires to be made.

Having now described my invention, what I claim as new therein, and desire to secure by Letters Patent, is as follows:

1. In a machine for applying pigment to phonograph or other sound records, the combination with means for carrying and rotating a cylindrical record, of a pigment-applying roller normally out of engagement with the record but adapted to be engaged with the end of the same and means for applying pigment to said roller, substantially as set forth.
2. In a machine for applying pigment to phonograph or other sound records, the combination with a mandrel on which the record is held frictionally, of a pigment-applying roller normally held out of engagement with the record but movable into engagement with the end thereof and means for applying pigment to said roller, substantially as set forth.
3. In a machine for applying pigment to phonograph or other sound records, the combination with a mandrel carrying a phonograph-record, of a pigment-applying roller normally out of engagement with said record, but movable into engagement therewith, means for applying pigment to said roller and a wiper engaging the roller during the application of the pigment to the same, substantially as set forth.
4. In a machine for applying pigment to phonograph or other sound records, the combination of a mandrel carrying a phonograph-record, a pigment-supply roller, a pigment-tank in which said supply-roller dips, and a pigment-applying roller normally in contact with the supply-roller, but movable into engagement with the end of the record, substantially as set forth.
5. In a machine for applying pigment to phonograph or other sound records, the com-

bination of a mandrel carrying a phonograph-record, a pigment-supply roller, a pigment-tank in which said supply-roller dips, a pigment-applying roller normally in contact with the supply-roller but movable into engagement with the record, and a wiper with which the applying-roller is normally engaged by the rotation of the supply-roller, substantially as set forth.

6. In a machine for applying pigment to phonograph or other sound records, the combination of a mandrel carrying a phonograph-record, a pivoted arm, a pigment-applying roller longitudinally adjustable on said arm and normally out of engagement with the record, but adapted to be engaged with the same, and means for applying pigment to said roller, substantially as set forth.

7. In a machine for applying pigment to phonograph or other sound records, the combination of a mandrel carrying a phonograph-record, a pivoted arm, a pigment-applying roller longitudinally adjustable on said arm and normally out of engagement with the record, a pigment-tank, and a supply-roller for furnishing pigment to said applying-roller, substantially as set forth.

8. In a machine for applying pigment to cylindrical sound-records, the combination of a rotary record-support, a pivoted arm, a pigment-applying roller slideable on said arm, and a spring for restoring said roller to its normal position on said arm, substantially as set forth.

9. In a machine for applying pigment to cylindrical sound-records, the combination of a rotary record-support, and a support carrying a pigment-applying roller, said supports being capable of relative movement to bring the roller into and out of engagement with the end of the sound-record, substantially as set forth.

10. In a machine for applying pigment to cylindrical sound-records, the combination of a rotary record-support, a support carrying a pigment-applying roller, said supports being capable of relative movement to bring the roller into and out of engagement with the end of the sound-record, and means for adjusting said roller in the direction of its axis, substantially as set forth.

This specification signed and witnessed this 21st day of September, 1904.

JOHN F. OTT.
